SAFETY SHUTOFF SYSTEM

Stanley S. Guelson, Milwaukee, Wis., assignor to
 Milwaukee Gas Specialty Company, Milwaukee,
 Wis., a corporation of Wisconsin

Application May 9, 1940, Serial No. 334,159

9 Claims. (Cl. 236—21)

This invention relates to improvements in safety shutoff systems for fuel burners and the like.

One of the main objects of the invention is to provide an improved multi-controlled safety shutoff system which is operable to maintain a supply of fuel to a burner as long as a pilot light in juxtaposition to the burner is burning and as long as other means, such as a thermostat or other condition responsive device, is operative to permit the same, and which system is operable automatically to shut off the supply of fuel to the burner when the pilot light is extinguished and also when the other means, such as the thermostat or other condition responsive device, is operated to accomplish that result as, for example, where such other means is a thermostat, when the temperature adjacent the same reaches a predetermined maximum, or where such other means is some other form of condition responsive device, upon some other abnormal, defective, or insufficient functioning or non-functioning of the apparatus.

It is a further and more specific object of the invention to provide an improved safety shutoff system characterized by the combination with a diaphragm or other equivalent valve in the fuel supply pipe leading to the main burner, of a vent or bleed tube for venting said valve, a fuel supply pipe adapted to receive fuel from said vent or bleed tube and leading to a normal pilot burner in juxtaposition to the main burner, a second fuel supply pipe also adapted to receive fuel from said vent or bleed tube and leading to a second pilot burner in juxtaposition to the normal pilot burner, means responsive to the heat of either or both of the pilot burners and operative to shut off the supply of fuel to both pilot burners when the pilot lights go out, whereupon there is a building up of pressure at the diaphragm or equivalent valve with an accompanying operation of said valve to closed position; the thermostatic or other responsive device, when acted upon by any outside influence, operates independently to shut off the supply of fuel to said second pilot burner with an accompanying building up of pressure at the diaphragm or equivalent valve, thereby causing said valve to close.

Another object of the invention is to provide a thermoelectric safety shutoff system embodying the features herein disclosed.

Another object of the invention is to use the bleed fuel of constant and sufficient quantity and pressure from the diaphragm or equivalent

valve in the fuel supply pipe leading to the burner as the pilot burner fuel.

Another object is to provide a system in which a 100% shutoff may be secured; also a system in which the pilot flame responsive means comprises an electromagnetic valve and a thermocouple placed in position to be heated by the pilot light or lights and so located that it may be energized by the flames from either or both of the pilot burners and connected in circuit with the electromagnet, and a system of the character described having reset means for resetting the electromagnetic valve and in which the diaphragm or equivalent valve in the fuel supply pipe leading to the burner cannot open during the resetting operation.

Another object is to provide a system in which the reset means is operative to establish a flow of fuel to the normal pilot burner and in which means is provided to interrupt or shut off the flow of fuel to the other pilot burner during the resetting operation.

Another object of the invention is to provide a safety shutoff system of the class described in which simple types of thermostats or other condition responsive devices, or small electric valves or the like, may be employed to control the action of the diaphragm valve.

Another object is to provide a diaphragm valve which will fail safe or operate to closed position if the diaphragm breaks.

Further features and advantages of the invention will be apparent from the following detailed description taken in connection with the accompanying drawings, in which:

Figure 1 is a more or less schematic view showing a thermoelectric safety shutoff system embodying the present invention;

Figure 2 is a vertical section through the diaphragm valve of the system shown in Figure 1;

Figure 3 is an axial section through the electromagnetic valve of the system shown in Figure 1;

Figure 4 is a section through the thermostatic valve of the system shown in Figure 1; and

Figure 5 is a section through the pilot burner structure.

The invention can be embodied in a wide variety of forms for use with a wide variety of devices, but for purposes of illustration the invention has been shown more or less schematically as embodied in a manner automatically to close a valve in a fuel supply pipe leading to a burner when the pilot light for the burner goes out and

also when a thermostat is operated to accomplish that result.

In Figure 1 of the drawings, the burner 10 is any suitable or preferred main burner, such as the burner of a room or space heater, water heater, floor furnace, or any other burner. A fuel supply pipe 11 leads to the burner 10 for the delivery of gaseous or other fuel thereto through the mixing chamber 11', and a suitable valve, such, for example, as a diaphragm valve 12, is positioned in the pipe 11.

The diaphragm valve 12 has a partition 13 dividing the interior thereof into an inlet chamber 14 and an outlet chamber 15. Formed in the partition 13 is a valve opening 16 having a valve seat 17 formed about the upper end thereof. A valve casing part 18 is suitably secured to the main valve casing part, and clamped in place marginally by the casing part 18 is the flexible diaphragm 19. The diaphragm 19 divides the space between the valve casing part 18 and a second partition 20 on the main valve body into an inner diaphragm chamber 22 and an outer diaphragm chamber 23. The partition 20 is shown as formed separate from the main valve body to facilitate mounting the valve 28 and its valve stem in place. This may vary.

The inlet chamber 14 of the valve communicates through openings 24 in the partition 20 with the interior of the inner diaphragm chamber 22 so as to subject the inner side of the diaphragm 19 to the pressure of the fuel in the fuel supply pipe 11. The diaphragm 19 carries at the center thereof the valve stem 26 which has reciprocatory movement in the partition 20. The valve member 28, shown as of disk-like form, is carried by the inner end of the stem 26 and is adapted to seat upon the valve seat 17 to shut off the flow of fuel to the burner 10. The diaphragm 19 is shown as provided with weights 30 clamped in place upon the stem 26 for actuating the valve member 28 to closed position, as shown in Figure 2, when pressure is allowed to build up in the outer diaphragm chamber 23 by the closing of one or both of the vents or bleed tubes, as will hereinafter appear. The diaphragm valve is of a character to fail safe—that is, the weights 30 will operate the valve member 28 to closed position to shut off the flow of fuel to the burner 10 if the diaphragm breaks.

The valve stem 26 has a diametrical orifice 35 which opens from the inlet chamber 14 into an orifice 36 which extends axially through the valve stem 26 and opens at the outer end of the valve stem into the outer diaphragm chamber 23. A pipe or tube 38 leads from the outer diaphragm chamber 23 to the inlet 39 of the electromagnetic valve designated in its entirety at 40.

The particular electromagnetic valve selected for illustration comprises a valve body 41 having, in addition to the inlet 39, a pair of outlets 42 and 43.

A magnet mounting cup 44 of "Bakelite" or any other suitable or preferred insulating material is mounted upon the outer end of the valve body 41 and closes the outer end of the bore 45. The cup 44 has, at its inner end, an integral extension which fits into the counterbore 46, and the cup 44 may be fastened in place by screws, or in any other suitable or preferred manner, preferably with a washer 47 between the cup 44 and the valve body.

The magnet housing is in the form of an outwardly opening metal cup 48 mounted upon the mounting cup 44, for example by pressed fit en-

gagement of its outer open end in the mounting cup 44 at 49. The magnet cup 48 is reduced at its inner end at 50, and the armature housing, which is also in the form of an outwardly opening metal cup 51, is mounted on the cup 48, for example by pressed fit engagement of its outer open end telescopically over the reduced inner end of the cup 48. The inner end of the cup 51 is preferably reduced as shown.

The electromagnet comprises a generally U-shaped magnet frame 54 positioned within the cup 48 with its legs extending through openings in the inner end of the cup 48 and presenting pole ends within the armature cup 51. The form of the magnet frame may be varied and variations in the other parts of the apparatus are also contemplated within the scope of the present invention. The particular magnet frame 54 selected for illustration has a threaded stud 55 integral therewith, or welded or otherwise joined thereto. This stud 55 extends into an opening or recess 56 in the mounting cup 44 and has threaded engagement with a nut 58 for clamping the magnet frame 54 rigidly and, at the same time, removably in place. The nut 58 has a kerf for engagement by a screw driver or other suitable tool, and a sealing washer 59 may be provided between the nut 58 and the inner end of the recess 56.

Fixed in the mounting cup 44, as, for example, by molding the insulating material of the cup thereto and extending endwise from the cup 44, are a pair of spaced metallic terminal connectors 60 and 61 having aligned openings 62. The terminal connectors 60 and 61 are split outwardly of the openings 62, and the split portions are adapted to be clamped together by screws 64.

The magnet coil 66 surrounds the legs of the magnet frame 54, and the leads or end of this coil have their bared ends connected to the terminals 60 and 61 in a manner to have good conducting contact therewith, as, for example, at 68 and 69. The coil 66 is preferably covered with insulation between the bared ends. If desired, additional insulation may be provided between the turns of the coil and the legs of the magnet frame and between the inner end of the cup 48 and the adjacent end of the coil.

The armature 71 is disposed in the armature cup 51 and is adapted to be held in attracted position against the pole ends of the magnet frame 54 when the electromagnet is energized, as will presently appear. The armature 71 is of disc-like form and is secured to the outer end of a reciprocating valve stem 72. The attachment of the armature 71 to the valve stem 72 may be sufficiently loose or otherwise of a character to permit self-accommodation of the armature to the pole ends of the magnet frame by a generally universal movement of the armature upon the outer end of the valve stem. The stem 72 is disposed generally concentrically of the armature housing 51 and extends inwardly for reciprocating movement through an opening 73 in the inner end of the housing 51.

The valve member 75 is fixed by a pin 76 upon the inner end of the valve stem 72, preferably for some relative movement thereon, so as to have self-accommodating seating engagement with the cooperating valve seat 78 at the outer end of the valve seat member 79. Packing 80 of felt or other suitable or preferred material is interposed between the bottom of the armature housing 51 and a metal valve spring seating disk 82. The valve spring 83 is in the form of

a coiled spring interposed between the valve member 75 and the spring seating disk 82 and centered, if desired, at opposite ends about the integral hub-like portions on the valve member 75 and valve seating disk 82. The spring 83 resiliently moves the armature 71 to retracted position and the valve member 75 to closed position seating upon the valve seat 78 to shut off the flow of fuel to the outlets 42 and 43 when the electromagnet is deenergized.

The disk 82 seats inwardly upon a shoulder in the bore 45, and the action of the spring 83 tends to compress the packing 80 and maintain same in sealing engagement with the bore 45 and with the valve stem 72, thus tending to seal the interior of the armature housing 51 from the gaseous or other fuel which passes through the valve body and to seal the valve body against the escape of fuel out around the magnet mounting cup and armature housing assembly. The device is further sealed against the escape of fuel by the washer 47.

A reset stem 88 extends through the inner end of the valve body 41. This reset stem is mounted coaxial with the valve 75 and for reciprocatory movement. The stem 88 is provided at its outer end with a reset stem knob or button 89.

Fixed upon the stem 88 for reciprocatory movement therewith is a reset member 90 which has abutting engagement with a spring disk 92. The spring disk 92 is slidably in the cooperating cylinder part of the valve housing and constitutes a reset guide in the resetting operation. A spring 95, shown as of coiled form, is interposed between this disk 92 and the valve seat member 79. A fuel flow interrupter spring 96 is interposed between the spring disk 92 and a flow interrupter disk valve 98. A retainer is provided at 99 for limiting inward movement of the disk valve 98 relative to the reset stem 88.

The disk valve 98 is adapted to seat upon the valve seat 100 at the adjacent end of the valve seat member 79 to shut off or interrupt the flow of fuel to the outlet 43 during the resetting operation and until the valve member 75 is held in open position by the thermoelectric current and the reset stem 88 is released. The reset member 88 has a tapered or generally conical portion which, under the action of the spring means, is held seated against a cooperating annular shoulder or seat on the valve body to seal the opening through which the reset stem 88 extends when the reset stem is positioned as shown in Figure 3.

The pilot burner means 112 comprises two pilot burners 118 and 118', the body portion of which is cast or formed integrally as shown in Figure 5. The pilot burner 118' constitutes the normal pilot burner. The side or pilot burner part 118' is mounted in juxtaposition to the main burner 10 and remains lighted in the manner presently to appear for the purpose of lighting the main burner.

When the valve member 75 is open, fuel is supplied through the outlet 42 of the electromagnetic valve 40 and connected pipe or tube 110 to the normal pilot burner 118'. Also, when the valve member 75 and flow interrupter disk valve 98 are open as shown in Figure 3, fuel is supplied through the other outlet 43 of the electromagnetic valve and a connected pipe or tube 114 to the other pilot burner. The flow of fuel through the tube 114 is controlled by a condition responsive device shown in the form of a thermostatic valve 116. It is to be understood that

other condition responsive devices operated by other abnormal, defective, or insufficient functioning or non-functioning of the apparatus are contemplated within the scope of the broader aspects of the present invention.

It will be noted that the outlet 42 opens out through the valve seat member 79 and the body of the electromagnetic valve outwardly of the valve seat 100 and between this valve seat 100 and the valve seat 78 at the outer end of the valve seat member 79. Thus, fuel passes out through the outlet 42 as long as the valve member 75 is open, and as long as the valve member 75 and flow interrupter disk 100 are both open, fuel passes out through the outlet 43. The seating of the flow interrupter disk 98 upon the valve seat 100 during the resetting operation shuts off the flow through the outlet 43 without shutting off the flow through the outlet 42.

The integrally cast body portion of the two pilot burners 118 and 118' has a recess 119 into which the fuel from the pipe 110 is delivered through an orifice 120; also a second recess 121 into which the fuel from the pipe 114 is adapted to be delivered through an orifice 122. The recess 119 has air inlet openings 123, and the mixture of air and fuel at the pilot burner 118 passes through a Venturi opening 124 to the pilot tip 111 from which it is discharged through an axial port 125 and a lateral port 126 to maintain, when ignited, the pilot flames indicated at 127 and 128. The recess 121 also has air inlet openings 130, and the mixture of air and fuel at the pilot burner part 118 passes through a Venturi opening 132 to the pilot tip 115 from which it is discharged through an axial port 133 and a lateral port 134 to maintain, when ignited, the pilot flames indicated at 135 and 136.

The orifice 36 at the diaphragm valve is larger than the normal pilot burner orifice 120. The area of the orifice 120 plus the area of the second pilot burner orifice 122 is equal to, or larger than, the area of the orifice 36, so that when the valve member 75 and the valve 181 (Figure 4) are open, the gas or other fuel will bleed off from the outer diaphragm chamber 23 as fast, or faster than the inflow of gas into the chamber 23 through the orifice 36. In operation, the pilot burner 118' is ignited from the pilot burner 118, and vice versa. The orifice 122 is preferably larger than the orifice 120.

The differences in area between the orifice 36 and the orifice 120 is such that when the pilot burner 118' is operating normally and correctly there will not be sufficient fuel bleeding from the outer diaphragm chamber 23 through the pipe 110 to allow the pressure of the fuel in the pipe 11 to open the diaphragm valve. The combined areas of the orifices 120 and 122 is sufficient to pass enough fuel so as to allow the fuel to bleed from the outer diaphragm chamber 23 fast enough to permit the diaphragm valve to be opened and held open by the pressure of the fuel in the pipe 11.

While any other suitable or preferred form of thermocouple and lead connection may be employed within the scope of the broader aspects of the present invention, the particular thermocouple and lead connection shown in the drawings are of the general character disclosed and claimed in Oscar J. Leins Patent No. 2,126,564, granted August 9, 1938. The thermocouple, designated in its entirety at 140, comprises an outer tubular metallic thermocouple member 141 and an inner metallic thermocouple member 142

disposed within the outer thermocouple member and joined at one end to the outer thermocouple member to form the thermal junction 143 which is positioned to be heated by the pilot flames 128 and 136.

An inner lead conductor 144 is joined to the inner thermocouple member to form an internal thermal junction 145, and an outer tubular lead conductor 146 is connected to the outer tubular thermocouple member—for example, through a sleeve 147—to form a third thermal junction 148. The outer lead conductor and outer tubular thermocouple member enclose the inner lead conductor and inner thermocouple member. The inner lead conductor 144 is insulated from the outer lead conductor 146, for example, by a wrapping of insulation on the inner lead conductor.

The thermocouple is supported between the pilot burners 118 and 118' by the cross part integrally connecting the same and in position to be energized by the flames from either or both of the pilot burners. The pilot tips 111 and 115 may be mounted detachably as shown, or otherwise, on the respective pilot burners. As one suitable manner of supporting the thermocouple, the sleeve 147 of the thermocouple has an enlarged portion at 150 which seats at 151 on the cross part integrally connecting the pilot burners. A nut 152 has threaded engagement with a boss on the part connecting the pilot burners and cooperates with the enlarged portion 150 to clamp the thermocouple removably in place.

The pilot burner tips are developed to produce satisfactory ignition characteristics for each particular installation.

The inner and outer lead conductors are preferably of a character that will permit bending as desired to permit disposing the thermocouple in any desired position. At the end opposite the end at which the thermocouple is disposed the inner lead conductor 144 extends from the outer lead conductor 146 and has a metallic terminal sleeve 160 fixed thereon in good conductive contact therewith and spaced from the end of the outer lead conductor 156. An insulating sleeve 162 is interposed between the terminal sleeve 160 and the adjacent end of the outer lead conductor 146.

The thermocouple is connected to the terminals 60 and 61 of the electromagnetic valve by slipping the terminal end of the thermocouple lead means through the opening 62 in the terminal 61 and into the opening 62 in the other terminal 60, with the terminal sleeve 160 in the opening in the terminal 60 and the end of the tubular thermocouple lead 146 in the opening 62 in the other terminal 61. The screws 64 are then tightened to clamp the split portions of the terminals 60 and 61 into good conductive contact and gripping engagement with the terminal sleeve 160 and the tubular lead 146 respectively. The thermocouple is disconnected from the electromagnetic valve by loosing the screws 64 and withdrawing the terminal end of the thermocouple leads from the terminals 60 and 61.

For purposes of illustration, the invention is shown in connection with a water heater, and the thermostatic valve 116 for controlling the flow of fuel through the pilot supply tube 114 is shown as comprising a rod and tube form of thermostat. As already pointed out, however, other forms of thermostats and other forms of condition responsive devices for controlling the flow of fuel through the vent or bleed tube 114 are contemplated.

The thermostatic valve 116 selected for illustration comprises a body or valve casing 175 having an inlet 176 connected by a part of the pipe 114 to receive fuel from the outlet 43 of the electromagnetic valve 40 and an outlet 177 connected by the other part of the pipe 114 to deliver the fuel to the tip 115 of the pilot burner 118. The inlet 176 opens into an inlet chamber 178 in the casing 175, and the outlet 177 leads from an outlet chamber 179. A valve opening 180 provides for communication between the inlet chamber 178 and the outlet chamber 179, and this valve opening is controlled by a valve 181. A spring 182, interposed between the valve 181 and a removable cap 183, presses the valve 181 toward the seat 184.

The valve casing 175 is externally threaded at 185 to be mounted in the shell or wall 186 of a water heater as shown, for example, in Figure 1. The tube 187 extends into the tank 186 for contact with the water therein. The rod 188 is disposed axially within the tube 187, with its inner end cooperating with a plug or cap 189 closing the inner end of the tube 187. The outer end of the rod 188 is pointed, and this pointed outer end engages an arm 190 which is disposed within the valve casing 175 and which is fulcrumed at one end upon the pointed inner end of an adjusting screw 191. The screw 191 is adjustable in the casing 175 for the purpose of adjusting the temperature at which the thermostat is operable to close the valve 181. The opposite end of the arm 190 cooperates with the valve stem 192 so that until the temperature at which the valve 181 is to close is reached, the rod 188, by its cooperation with the arm 190, holds the valve 181 against the action of the spring 182.

The tube 187 is composed of a thermally responsive metal which has a coefficient of expansion different from the coefficient of expansion of the metal rod 188. As a result, when the temperature is reached at which the valve 181 is to close, the expansion of the tube 187 releases the action of the rod 188 on the arm 190 sufficiently to permit the spring 182 to move the valve 181 to closed position, thereby shutting off the flow of fuel through the vent or bleed tube 114 to the tip 115 of the pilot burner 118.

To start the operation of the system, the following sequence is followed:

The reset stem 88 is pressed inwardly to actuate the valve member 75 to open position and the armature 71 to attracted position in contact with the pole faces of the magnet frame 54. This allows the fuel to flow through the outlet 42 and pilot line 110 to the normal pilot burner 118 where the same is ignited. The stem 88 is held in depressed position until the flame 128 has heated the thermocouple sufficiently to energize the magnet 54 so that it will hold the armature 71 attracted thereto and, thereby, the valve member 75 in open position. The flow interrupter disk 98 seats upon the seat 100 to shut off the flow of fuel to the outlet 43 as long as the stem 88 is pressed inwardly.

When the magnet is energized sufficiently to hold the armature 71 in attracted position and the valve member 75 in open position, the reset stem 88 is released, thus allowing the flow interrupter disk to return to open or normal operating position. Fuel then flows out through the outlet 43 and pilot line 114 to the thermostatically controlled valve at 116. Assuming that the valve at 116 is open, this fuel is delivered to the tip 115 of the pilot burner 118 through the pilot line 114

where it is ignited by the pilot burner 118. If, on the other hand, the pilot burner is not lighted to produce the thermoelectric current for holding the armature in attracted position and the valve 75 open, the armature 71 will be actuated to retracted position and the valve 75 to closed position upon release of the reset stem 88.

With the thermostatic or other condition responsive valve 181 in the vent or bleed tube 114 open, both of the vents or bleed tubes operate to vent or relieve the pressure of the fuel delivered to the outer side of the diaphragm through the orifice 36 fast enough to permit the diaphragm valve to be opened and held open by the pressure of the fuel in the pipe 11. The orifice 120 is smaller than the orifice 36 and is designed definitely to prevent fuel from bleeding from the outer diaphragm chamber 23 in quantity sufficient to enable the diaphragm valve to open, whereas the orifice 122 may or may not be large enough to allow the diaphragm valve to open. The orifice 36 at the diaphragm valve 12 being larger than the orifice at 120, it will be obvious that when the flow or escape of fuel through the vent or bleed tube 114 is shut off, the delivery of fuel into the outer diaphragm chamber 23 through the orifice 36 will cause pressure to build up in the outer diaphragm chamber. This results in overcoming the pressure of the fuel in the main fuel supply pipe on the inner side of the diaphragm 18 sufficiently to permit actuation of the valve 28 to closed position, for example, by the weights 30, to shut off the supply of fuel to the main burner 10.

In the illustrated embodiment of the invention, when the temperature of the water in the tank 186 reaches the temperature at which it is desired automatically to shut off the supply of fuel to the main burner 10, the tube and rod thermostat 187 and 188 releases the thermostatic valve 181, which valve thereupon is closed by the spring 182, shutting off the supply of fuel through the vent or bleed tube 114 and thereby the supply of fuel to the pilot tip 115. The orifice 120 for the bleed tube 110 being smaller than the orifice 36, pressure builds up in the outer diaphragm chamber 23 and the diaphragm valve 28 is actuated to closed position to shut off the supply of fuel to the main burner 10. The supply of fuel, however, continues through the pipe 38, inlet 39 of the electromagnetic valve 40, outlet 42, and tube 110, to the pilot tip 111 to maintain the pilot flames at 127 and 128 so that when the temperature drops or the other condition to which the valve 181 is subjected is corrected, the flow of fuel thereupon again set up to the pilot jet 115 through the tube 114 will be ignited to provide the multi-frame pilot.

If, on the other hand, both of the pilot burners are extinguished so that the thermal junction 143 is no longer heated sufficiently to set up the thermoelectric current for energizing the electromagnet to hold the armature 71 attracted and the valve 15 open, the armature 71 is released and the spring 83 moves the armature to retracted position and the electromagnetic valve 75 to closed position, shutting off the flow of fuel not only through the tube 110 to the pilot tip 111, but also the flow of fuel through the tube 114 to the pilot tip 115. As a result, pressure builds up in the outer diaphragm chamber 23, and the diaphragm valve 28 is closed to shut off the supply of fuel to the main burner.

From the foregoing description, it will be ap-

parent that the present invention provides for the use of bleed gas or fuel from the diaphragm valve as the pilot burner fuel, that it provides a 100% shutoff, that the diaphragm valve cannot open during the resetting operation, that the system will fail safe if the diaphragm breaks, and that simple types of thermostats or small electric valves or other suitable control devices may be employed to control the action of the diaphragm valve.

I do not intend to be limited to the precise details shown or described.

I claim:

1. In combination, a main burner, a fuel supply pipe leading to said burner, a valve in said pipe, said valve having a diaphragm subject on one side to the pressure of the fuel in said pipe and having a diaphragm chamber on the other side thereof, means for constantly bleeding fuel into said diaphragm chamber from the fuel supply pipe anterior of said valve, a pair of vents for venting said diaphragm chamber, said valve being opened and held open by the pressure of the fuel in said pipe on said diaphragm when both of said vents are open, and means operable to open and close one of said vents independently of the other vent, said other vent being of a size to prevent, when said other vent only is open, venting said diaphragm chamber sufficiently to permit said diaphragm valve to be opened and held open by the pressure of the fuel in said pipe.

2. In combination, a main burner, a fuel supply pipe leading to said burner, a valve in said pipe, said valve having a diaphragm subject on one side to the pressure of the fuel in said pipe and having a diaphragm chamber on the other side thereof, means for constantly bleeding fuel into said diaphragm chamber from the fuel supply pipe anterior of said valve, a pair of vents for venting said diaphragm chamber, said valve being opened and held open by the pressure of the fuel in said pipe on said diaphragm when both of said vents are open, means operable to open and close one of said vents independently of the other vent, and a second means operable to open and close said other vent, said other vent being of a size to prevent, when said other vent only is open, venting said diaphragm chamber sufficiently to permit said diaphragm valve to be opened and held open by the pressure of the fuel in said pipe.

3. In combination, a main burner, a fuel supply pipe leading to said burner, a valve in said pipe, said valve having a diaphragm subject on one side to the pressure of the fuel in said pipe and having a diaphragm chamber on the other side thereof, means for constantly bleeding fuel into said diaphragm chamber from the fuel supply pipe anterior of said valve, a pair of vents for venting said diaphragm chamber, said valve being opened and held open by the pressure of the fuel in said pipe on said diaphragm when both of said vents are open, means operable to open and close one of said vents independently of the other vent, and second means operable to open and close both of said vents, said other vent being of a size to prevent, when said other vent only is open, venting said diaphragm chamber sufficiently to permit said diaphragm valve to be opened and held open by the pressure of the fuel in said pipe.

4. In combination, a main burner, a fuel supply pipe leading to said burner, a main valve in said pipe, said valve having a diaphragm subject on one side to the pressure of the fuel in said

pipe and having a diaphragm chamber on the other side thereof, means for constantly bleeding fuel into said diaphragm chamber from the fuel supply pipe anterior of said valve, a pair of bleed tubes for venting said diaphragm chamber, said valve being opened and maintained open by the pressure of the fuel in said pipe on said diaphragm only when both of said bleed tubes are operating to vent said valve, said bleed tubes constituting supply tubes for pilot lights at least one of which is located in juxtaposition to said burner, and condition responsive means having a safety position for shutting off the flow of fuel through one of said bleed tubes and an operating position for the flow of fuel through said tube, the other tube having a vent of a size to prevent, when said other tube only is open, venting said diaphragm chamber sufficiently to permit said diaphragm valve to be opened and held open by the pressure of the fuel in said pipe.

5. In combination, a main burner, a fuel supply pipe leading to said burner, a valve in said pipe, said valve having a diaphragm subject on one side to the pressure of the fuel in said pipe and having a diaphragm chamber on the other side thereof, means for constantly bleeding fuel into said diaphragm chamber from the fuel supply pipe anterior of said valve, a pair of bleed tubes for venting said diaphragm chamber, said valve being opened and maintained open by the pressure of the fuel in said pipe on said diaphragm only when both of said bleed tubes are operating to vent said valve, said bleed tubes constituting supply tubes for pilot lights at least one of which is located in juxtaposition to said burner, condition responsive means having a safety position for shutting off the flow of fuel through one of said bleed tubes and an operating position for the flow of fuel through said one tube, the other tube having a vent of a size to prevent, when said one tube is closed and said other tube is open, venting said diaphragm chamber sufficiently to permit said diaphragm valve to be opened and held open by the pressure of the fuel in said pipe, and means responsive to the heat of the pilot lights and operable to shut off the flow of fuel through both of said bleed tubes when the pilot lights go out.

6. In a safety shutoff system of the class described, a main burner, a fuel supply pipe leading to said burner, a diaphragm valve in said pipe, said valve having a diaphragm subject on one side to the pressure of the fuel in said pipe and having a diaphragm chamber on the other side thereof, means for constantly bleeding fuel into said diaphragm chamber from the fuel supply pipe anterior of said valve, a vent tube for venting said diaphragm chamber, a fuel supply pipe adapted to receive fuel from said tube and leading to a normal pilot burner in juxtaposition to the main burner, a second fuel supply pipe also adapted to receive fuel from said tube and leading to a second pilot burner in juxtaposition to the normal pilot burner, means responsive to the heat of the pilot burner and operative to shut off the supply of fuel to both pilot burners when said pilot burners go out, whereupon there is a building up of pressure in the diaphragm chamber with an accompanying operation of said

valve to closed position, and a condition responsive device operative to shut off the supply of fuel to said second pilot burner with an accompanying building up of pressure in the diaphragm chamber and operation of said valve to closed position, the normal pilot burner affording a vent for said diaphragm chamber of a size to prevent, when said vent is open, venting said diaphragm chamber sufficiently to permit said diaphragm valve to be opened and held open by the pressure of the fuel in said pipe.

7. In combination, a main burner, a fuel supply pipe leading to said burner, a valve in said pipe, said valve having a diaphragm subject on one side to the pressure of the fuel in said pipe and having a diaphragm chamber on the other side thereof, means for constantly bleeding fuel into said diaphragm chamber from the fuel supply pipe anterior of said valve, a pair of vents for venting said diaphragm chamber, two pilot lights one receiving fuel from one of said vents and the other receiving fuel from the other of said vents, and thermoresponsive means for opening and closing one of said vents, said valve being opened and held open by the pressure of the fuel in said pipe only when both of said vents are open.

8. In combination, a main burner, a fuel supply pipe leading to said burner, a valve in said pipe, said valve having a diaphragm subject on one side to the pressure of the fuel in said pipe and having a diaphragm chamber on the other side thereof, means for constantly bleeding fuel into said diaphragm chamber from the fuel supply pipe anterior of said valve, a pair of vents for venting said diaphragm chamber, said valve being opened and held open by the pressure of the fuel in said pipe only when both of said vents are open, means for closing one of said vents, and means for delivering fuel from said fuel supply pipe through the other vent when said first mentioned vent is closed and when the valve in said fuel supply pipe is closed.

9. In combination, a main burner, a fuel supply pipe leading to said burner, a valve in said pipe, said valve having a diaphragm subject on one side to the pressure of the fuel in said pipe and having a diaphragm chamber on the other side thereof, means for constantly bleeding fuel into said diaphragm chamber from the fuel supply pipe anterior of said valve, a pair of vents for venting said diaphragm chamber, said valve being opened and held open by the pressure of the fuel in said pipe on said diaphragm when both of said vents are open, a valve member operable to open and close one of said vents independently of the other vent, a second valve member operable to open and close both of said vents, a thermocouple positioned to be heated by a flame supplied with fuel by the other vent, an electromagnet connected in circuit with said thermocouple, and an armature for said electromagnet, said second valve member being held in open position when the armature is held attracted to said electromagnet and operable to closed position to close both of said vents when the armature is retracted.
